UNITED STATES PATENT OFFICE.

CHARLES D. YOUNG, OF PITTSBURGH, PENNSYLVANIA.

AUTOMATIC STOKER.

1,113,398.

Specification of Letters Patent.

Patented Oct. 13, 1914.

Application filed May 17, 1911. Serial No. 627,830.

To all whom it may concern:

Be it known that I, CHARLES D. YOUNG, a citizen of the United States, residing at Pittsburgh, in the county of Allegheny and 5 State of Pennsylvania, have invented certain new and useful Improvements in Automatic Stokers, of which the following is a specification.

The invention relates to automatic stokers 10 of the underfeed type and particularly to the grate construction employed. The invention has for its principal objects; the provision in an underfeed stoker of a grate construction particularly adapted to prevent the coal 15 from caking over the grates; the provision of a construction arranged to secure a disturbance in and breaking up of the mass of coal passing laterally from the underfeed trough to the grate; the provision of a grate arrangement whereby the feed laterally from the 20 troughs is increased, thus reducing the thickness of the body of coal over the troughs; the provision of a grate contour particularly adapted for use with coking coal, and in 25 which the rocking members are moved a maximum distance at the points in the body of fuel where the fuel has been consumed and a less distance adjacent the troughs where the coal is only partly consumed; the provision 30 of an improved drop grate; and the provision of an improved and simplified arrangement for operating the grates. One embodiment of the invention is illustrated in the accompanying drawings, wherein:—

35 Figure 1 is a section taken through a locomotive fire-box above the grates and shows in plan view my improved grate and stoker mechanism, a part of the grate bars being broken away to more clearly disclose the 40 operating parts, Fig. 2 is an enlarged transverse section on the line II—II of Fig. 1, Fig. 3 is an enlarged transverse section on the line III—III of Fig. 1, and Fig. 4 is a detail of a slightly modified construction.

45 As indicated in Fig. 1, the furnace is provided with two longitudinally extending underfeed troughs 1 and 2, although the number may be varied to suit conditions, and these troughs are supplied with coal by 50 means of the operating mechanism shown at the left hand end of Fig. 1, such feeding mechanism being immaterial in so far as the present invention is concerned. The underfeed troughs 1 and 2 are shown as provided 55 with three auxiliary feed pistons 3, 4 and 5,

but this is also immaterial in so far as the present invention is concerned, and any number of feed pistons desired may be employed. Along each side of the furnace extends the fixed bars 6 and 7 (Fig. 2) which 60 bars carry the upwardly inclined sets of fingers 8 and 9. On each side of each of the troughs 1 and 2 are the sets of downwardly inclined grate fingers 10, 11, 12 and 13, which sets of grate fingers, as shown, are 65 cast integral with the upper edge portions 14' of the troughs 1 and 2, although this obviously need not be the case. The openings 14 illustrated in Fig. 2 are for the circulation of air, such circulation of air tending to keep 70 the upper edges of the troughs and those portions of the troughs supporting the sets of grate fingers cool. At the center of the furnace is a non-rotary bar 15, and fitting over this bar 15 are U-shaped members 16 75 having integral therewith the upwardly inclined grate fingers 17 and 18. Also extending longitudinally of the furnace are the bars 19, 20, 21 and 22, which bars are mounted for rocking movement and carry the U- 80 shaped castings 23, each of which is provided with the two sets of fingers 24, and 25, for coöperating with the adjacent fixed sets of grate fingers, the set of fingers 24 being shorter than the set 25. 85

The purpose of inclining the grates in the manner just described and as illustrated in Fig. 2, is to secure the proper breaking up of the body of coal as it passes from the troughs, and to prevent such coal from caking 90 over the grates. The placing of the sets of fingers 10, 11, 12 and 13 below the upper edges of the troughs, tends to secure this result, and the inclination of the grates still further assists, as the tendency of the coal 95 is to move down the incline, and thus produce a break in the body of the coal above the edges of the troughs and prevent the coal from heaping up at such points. The making of the fingers 25 longer than the 100 fingers 24 is desirable, as by this arrangement a greater agitation of the fuel is secured at a point removed from the troughs, and consequently at a point at which the combustion is more complete than it is above 105 the fingers 24. The percentage of consumed matter is of course greater above the fingers 25, and the agitation of these fingers serves to keep the grate clean, while agitation by the fingers 24 tends to break up the coal 110

and prevent its caking without an undue loss of fuel such as would occur if a violent agitation at this point were produced.

As indicated in Fig. 2, the U-shaped castings carried by the rock bars 20 and 21 are provided with downwardly projecting arms 26 and 27, and these arms are pivotally connected to a rod 28 extending through the fire-box and connected at its outer end to a crank 29 carried upon a rock shaft 30. As indicated in Fig. 1, this rock shaft 30 extends forward past the front end of the fire-box and is provided at such front end with another crank 31 (Fig. 3), and connecting rod 32 extending inwardly and engaging an operating handle 33, by means of which the rock bars 20 and 21 may be operated. As shown in Fig. 1, the rock bars 19 and 22 are extended through the water leg of the furnace and are operated by means of handles 34.

The drop gate construction will be readily seen by reference to Figs. 1 and 3. This drop grate lies between the troughs 1 and 2, and consists of a single casting 36 having the upwardly projecting grate bars 37 and 38. This drop grate is pivoted at 39 as indicated in Fig. 3, and is operated by means of a link 40 pivoted at the free end of the grate. This link 40 is actuated by the bell-crank lever shown in Fig. 3, which bell-crank lever is pivotally supported upon a bracket 41 carried by the engine frame and has the two arms 42 and 43, the former being connected to the end of the link, and the latter serving as the handle for operating the grate. The dotted lines indicate the position of the parts when the grate is in open position. It will be noted that when the grate is in closed position, the arm 42 of the bell crank lever and the link 40 are in alinement. When the parts are in the position shown in the full lines, the weight of the handle 43 is sufficient to maintain the grate in its upper position without the use of catches or other fastening devices.

Another advantage incident to the grate above described resides in the fact that the grate extends from one trough to the other, so that when the grate is dropped to the dotted lines indicated in Fig. 3 a very large opening for dumping is provided, and no difficulty is experienced in getting the unburned fuel and ash out of the furnace, as is the case where a narrow drop opening is provided. The grate forms in effect a basket into which a large quantity of fuel can be raked with the assurance that the contents will be discharged upon the actuation of the handle 43.

The members 44, 45, 46 and 47 shown in Fig. 1, are integral grate castings extending from one trough to the other, and serving as bearing or supporting members for the bars 20 and 21, and for the pivots of the drop

grate. Any number of such supporting members may be used as are found necessary.

The front end of the rock bars 19, 20, 21 and 22 are supported by lugs 48 cast with the upper edge portions 14' of troughs 1 and 2, thus avoiding extending the rock bars 19, 20, 21 and 22 through the water leg of the furnace.

If desired, the bar 15 can be mounted to rock, as illustrated in the modification in Fig. 4, the member 16 in that case being provided with an arm 49 connected to the bar 28 by the link 50, the construction in other respects following that shown in Fig. 2.

Having thus described my invention and illustrated its use, what I claim as new and desire to secure by Letters Patent is the following:—

1. In a furnace, the combination with a pair of underfeed troughs extending longitudinally of the furnace, of an intermediate V shaped grate, and rock grates between the outer edges of such grate and the sides of the trough.

2. In a furnace, the combination with a pair of underfeed troughs extending longitudinally of the furnace, of a grate intermediate the troughs and having its surface sloping upwardly from its central portion toward the sides of the troughs, and inclined rock grates between the upper edges of such grate and the edges of the troughs.

3. In a furnace, the combination with an underfeed trough, of a set of fixed grate fingers inclined downwardly from the edge of the trough, another set of fixed inclined grate fingers opposing the first set of fingers below such first set and spaced away therefrom, and a rock bar intermediate the two sets of fingers and provided with oppositely projecting sets of fingers for coöoperating with the fixed sets of fingers.

4. In a furnace, the combination with an underfeed trough, of a set of fixed grate fingers inclined downwardly from the edge of the trough, another set of fixed inclined grate fingers opposing the first set of fingers below such first set of fingers and spaced away therefrom, and a rock bar intermediate the two sets of fingers and provided with oppositely projecting sets of inclined fingers for coöoperating with the fixed sets of fingers, the set of fingers on the side of the rock bar away from the trough being longer than the other set of fingers on the rock bar.

5. In combination in a furnace, a central fixed grate bar extending longitudinally of the furnace and provided with two sets of oppositely and upwardly inclined grate fingers, a side rocking grate bar lying on each side of the central grate bar and provided with two sets of inclined oppositely projecting grate fingers, and an underfeed trough adjacent the outer side of each side grate bar.

6. In combination in a furnace, a central fixed grate bar extending longitudinally of the furnace and provided with two sets of oppositely and upwardly inclined grate fingers, a side rocking grate bar lying on each side of the central grate bar and provided with two sets of inclined oppositely projecting grate fingers, and an underfeed trough adjacent the outer side of each side 10 grate bar and provided with outwardly projecting sets of fixed grate fingers.
7. In combination in a furnace, a longitudinally extending underfeed trough, a set of downwardly projecting fixed grate bar 15 fingers at each side of the trough, and a rock bar lying below such fingers on each side of the trough and provided with two sets of fingers, one of which sets normally projects upwardly and coöperates with the fixed set 20 of fingers.
8. In combination in a furnace, a longitudinally extending underfeed trough, a set of downwardly projecting fixed grate bar fingers at the side of the trough, and a rock 25 bar lying below such fingers and provided with two sets of fingers, one of which sets co-operates with the fixed set of fingers, and has fingers of less length than the other set carried by the rock bar.
9. In combination in a furnace, a longitudinally extending underfeed trough, a set of downwardly projecting fixed grate bar fingers at the side of the trough, and a rock bar lying below such fingers and provided 30 with two sets of fingers, one of which sets co-operates with the fixed set of fingers, and has fingers of less length than the other set carried by the rock bar, and a set of fixed 35 grate fingers lying below the rock bar and coöperating with the outer set of fingers on such rock bar.
10. In a furnace, a pair of underfeed troughs extending longitudinally of the furnace, and a V shaped drop grate pivoted on an axis extending longitudinally of the 45 troughs to swing transversely downward between the troughs and extending from one trough to the other, and means for operating the grate.
11. In a furnace, a pair of underfeed 50 troughs extending longitudinally of the furnace, and a V shaped drop grate pivoted on an axis extending longitudinally of the troughs to swing transversely downward between the troughs and extending from one 55 trough to the other, link mechanism for supporting the grate, and a handle in the ash pan and extending through the side thereof for operating the drop grate.
12. In a furnace, a pair of underfeed 60 troughs extending longitudinally of the furnace, and a V shaped drop grate pivoted on an axis extending longitudinally of the troughs to swing transversely downward between the troughs, a link pivoted to the free 65 edge of the grate, a bell crank lever pivoted adjacent the side of the ash pan and having its handle extending therethrough and its other end pivoted to the said link and adapted to be in approximate alinement therewith 70 when the grate is in its uppermost position.
- In testimony whereof I have hereunto signed my name in the presence of the two subscribed witnesses.
